United States Patent Office

Des. 187,586
Patented Apr. 5, 1960

187,586

WALL BLOCK

Albert R. Clanton, Pacoima, Calif., assignor to North Hollywood Concrete Tile Co., Hollywood, Calif., a co-partnership

Application December 23, 1958, Serial No. 53,881

Term of patent 14 years

(Cl. D18—2)

FIG. 1.

FIG. 2.

FIG. 3.

FIG. 4.

Fig. 1 is a perspective view of a wall block showing my new design;

Fig. 2 is a front elevational view thereof;

Fig. 3 is a side elevational view thereof; and

Fig. 4 is a plan view thereof.

I claim:

The ornamental design for a wall block, substantially as shown.
